UNITED STATES PATENT OFFICE

MILTON M. FRANKEL, OF BROOKLINE, MASSACHUSETTS

PERMANENT WAVE APPLIANCE

Application filed September 12, 1931. Serial No. 562,476.

This invention relates to appliances used for producing a so-called "permanent wave" and the main object of the invention is to provide a novel means for insulating the end of the permanent wave curling rod which is adjacent the scalp so as to prevent the possibility of the customer becoming burned by contact of the hot rod with the scalp.

In order to give an understanding of the invention I have illustrated in the drawings some selected embodiments thereof which will now be described after which the novel features will be pointed out in the appended claims.

Fig. 1 is a view illustrating a single permanent wave curling rod with the lock of hair wound thereon and having my shield applied thereto;

Fig. 2 is a perspective view of one form of shield member;

Fig. 3 is a perspective view of a different form of shield member;

Figs. 4 and 5 show the manner in which the shield member shown in Fig. 3 is applied to the curling rod, Fig. 5 being a section at right angles to Fig. 4.

In making a permanent wave a wisp or lock of hair is wound tightly on a curling rod and then a prepared pad is placed around the curl and clamped thereto after which the heating unit is applied to the exterior of the pad for producing the desired curl in the hair. During this operation the end of the rod which is adjacent the scalp is exposed and it is necessary to use considerable care to prevent this exposed end of the rod which becomes quite hot from contacting with the scalp and thus producing a burn.

My improvements provide a novel protector or shield which encloses the exposed end of the rod and gives this desired protection.

In the drawings I have shown a single permanent wave curling rod and its associated pad and electric heater but it will be understood, of course, that in making a permanent wave a number of these curling irons are used.

1 indicates one of these permanent wave curling rods about which is wound a lock 2 of hair, the lock of hair being tied to the end

of the rod by a suitable string 3 and the ends of the string being caught in the slit 4 with which these curling rods are usually provided.

5 indicates the usual pad which is placed around the lock or curl of hair after it is wound on the rod 1 and 6 indicates the usual clamp employed for clamping the end of the pad tightly about the curl 2. 7 indicates the usual electric heating device which encloses the pad and which supplies the heat necessary for producing the desired permanent wave effect.

The parts thus far described are such as are usually found in permanent wave appliances and form no part of my present invention.

In applying the curl or lock 2 of hair to the rod 1 it is customary to begin the winding a slight distance from the end 8 of the rod so that the slit end of the rod will be exposed beyond the end of the string 3. This exposed end of the rod becomes quite hot and unless great care is used it is apt to come in contact with the scalp and cause a burn.

As stated above my improvements relate to means for protecting the heated end 8 of the rod 1 so as to prevent it from contacting with the scalp. One form of protector or shield adapted for this purpose is indicated at 9 and is shown in Fig. 2. This protector 9 is a two-part member comprising the two parts 10 and 11. The part 10 is provided with a socket portion 12 adapted to receive the end 8 of the rod and with a flange portion 13, which, however, does not extend clear around the socket member 12. The member 11 is shown as pivoted to the flange 13 as indicated at 14 and said member is formed on one edge with the notch 15 adapted to embrace the rod when the two parts are closed and are in operative position. This protector will be made of some suitable heat-insulating material, such for instance as fibre or hard rubber.

In using the device the lock or curl of hair is wound on the curling rod and the pad is applied and clamped in position in usual way. After this is done the shield 9 may be applied. This is done by opening the two members of the shield as shown in Fig. 2 and then inserting the end 8 of the rod in the socket

member 12, the lock or curl of hair at this time passing from the scalp up the side of the socket member from which there is no projecting flange. The member 10 is then swung 5 into the dotted line position shown in Fig. 2 thereby closing the opening 16 in the flange 13. With the protector in this condition not only will the end 8 of the rod 1 be protected but also there will be a heat-insulating element 10 comprising the flange 13 and the pivoted section 11 interposed between the clamp 6 and the head. All the exposed metal parts of the permanent wave appliance which are adjacent the scalp are thus protected thereby eliminating any danger that the scalp may 15 become burnt.

In Figs. 3 and 4 I have shown a somewhat different embodiment of the invention. In this case the protector or shield is in the form 20 of a tube 20 of heat-insulating material which is formed in one side with an opening 21 to receive the end 8 of the rod. One side of the tube is cut away at 22 to form a throat leading to the opening 21. This form of insulator 25 is used by forcing the exposed end 8 of the rod laterally through the throat 22 into the opening 21 so that the end of the rod is located within the tube as shown in Fig. 4. The resiliency of the walls of the member 20 retains 30 it on the rod.

This protector or insulator will preferably be so applied to the rod that the extremity of the rod will be spaced somewhat from the walls of the tube. The device thus serves 35 to protect the end 8 of the rod 1 and prevent it from contacting with the scalp and since the protector is made of heat-insulating material it will not become hot enough to burn or injure the scalp. Both forms of my invention, therefore, provide protection against the burning of the scalp by contact therewith of the hot end 8 of the curling rod.

I claim:

1. In a permanent wave appliance, the 45 combination with a permanent wave curling rod about which a lock of hair is wound, the inner end of the rod being exposed beyond the first turn of the lock of hair, and means to heat said rod, of a protector of heat-insulating material enclosing the exposed end of the rod and insulating said end and preventing the latter from contacting with the scalp, said protector being separable from the rod and capable of being applied to the exposed end thereof after the lock of hair has been curled about the rod.

2. A permanent wave appliance comprising 50 a curling rod about which a lock or curl of hair is wound with the inner end of the rod exposed, a pad enclosing the curl, and a heating element enclosing the pad, in combination with a protector of heat-insulating material removably applied to and enclosing the exposed end of the rod and preventing 55 the latter from contacting with the scalp,

said protector being removable from and capable of being applied to the rod while the lock of hair is curled thereon.

3. A permanent wave appliance comprising 70 a curling rod about which a lock or curl of hair is wound with the inner end of the rod exposed, a pad enclosing the curl, and a heating element enclosing the pad, in combination with a protector of heat-insulating material, said protector having a socket portion 75 to receive and enclose the exposed end of the rod, and means to clamp said member to the rod and being removable from and capable of being applied to the rod while the lock of hair is curled thereon.

4. A permanent wave appliance comprising 80 a curling rod about which a lock or curl of hair is wound with the inner end of the rod exposed, a pad enclosing the curl, a heating element enclosing the pad, in combination with a protector of heat-insulating material, said protector comprising a two-part member, one part having a socket portion to receive the exposed end of the rod and a flange portion extending part way around 85 the socket member and the other part being in the form of a plate pivoted to the flange portion and provided with a recess to receive the rod when said part is in operative position.

5. A permanent wave appliance comprising 90 a curling rod about which a lock or curl of hair is wound with the inner end of the rod exposed, a pad enclosing the curl, a heating element enclosing the pad, in combination with a protector of heat-insulating material, said protector comprising a tubular member having its axis extending transversely to that of the curling rod and provided in one side with an opening through which the 95 exposed end of the curling rod is inserted.

In testimony whereof, I have signed my name to this specification.

MILTON M. FRANKEL.
